GARMENT

Agnes Alice Elkins, Elyria, Ohio

Application April 20, 1945, Serial No. 589,302

3 Claims. (Cl. 2-69.5)

1

My invention relates to a garment for infants and small children and relates more particularly to a garment which might be termed a blanket for sleeping and/or walking, or an outer covering for an infant or small child to be worn while in his crib, or as otherwise desired, and which will permit any normal activities of the child, as, for example, sitting, walking, creeping, lying, etc.

It is an object of my invention to provide a flat blanket type article so shaped that it may be placed around an infant or small child in such manner as to completely cover the child for sleeping without hampering the child's freedom of action in any way. Hence, the child, upon awakening, may move about in his crib without becoming uncovered.

Prior art so-called "sleeping bags" with which I am familiar have generally hampered the child's movement in various ways and certain of these garments have been tied to the bed or mattress in some manner. In most of these bags, the arms have been covered and held at the level of the shoulder of the child or lower level, but the child is thereby unable to raise its arms above its head. Other garments have confined the child to a restricted orbit of movement in his crib or bed and in practically all garments with which I am familiar the child is anchored in some degree in a definite predetermined position in the crib or bed.

The garment of my invention moves with the child, completely covering him at all times and permitting him to creep, stand, sit, or lie down, to move his arms or legs, or head or body in any way that he may choose and without danger of suffocation or strangling, due to mechanical restrictions of one kind or another.

Other objects of my invention and the invention itself will become increasingly apparent from the following description and drawings, in which drawings:

Fig. 1 is an enlarged plan view of the garment of my invention showing the triangular chest protecting portion of such garment folded back in position for use;

Fig. 2 is a front view of the garment of Fig. 1 showing the garment in use; certain portions of the garment being shown in dotted lines to illustrate the underparts of the same; and

Fig. 3 is a plan view of the garment of my invention in an open extended position.

With reference to the drawings, Fig. 3 shows the garment of my invention in its open extended flat form, as for laundering, etc. It will be noted that the improved garment consists in a pentagon shaped or five sided piece of blanket material, preferably, or for a summer garment, light weight knitted cotton or sateen material, or any suitable

material for covering a child against exposure similar to that which would be employed for a bed covering during any particular season. It is composed of a triangular portion 1 and a rectangular portion 2.

It is to be noted that the altitude C-d of the triangular portion A-B-C, formed by line A to B, B to C, and C to A, is slightly less than the altitude J-Z of the rectangle A-X-Y-B formed by the lines A to X, X to Y, Y to B and B to A, and that the point C of the triangle intersects the center line C-z of the garment.

A circular opening 10 of a neck size suitable to accommodate a baby's or small child's neck to be thrust therethrough, is provided in the garment centrally of the triangle A-B-C, described previously herein, and a zipper is provided from the said opening along the line of altitude to a point closely adjacent the peak C of the triangle, which peak C, in the position of initial fold F-G, as shown in Fig. 1, is positioned lower than the points A and B of the triangle when the triangle F-C-G is formed by folding back said portion of the original triangle, as shown in Fig. 1.

A soft collar 10a preferably of knitted material is disposed about the neck opening 10 and attached thereto assuring protection and covering around the neck. It also prevents any possible chafing or irritation of the neck.

Hence, when the zipper or other fastening shown at 11 is open and the child's head is placed through the neck and fastener openings 10 and 11, the folded portion of the garment becomes a cover for the shoulders and chest 35 of the child, as shown in Fig. 3. The fastener 11 is then closed and one edge B-y preferably of the rectangle folded in and over the front of the child to a point 12 where the corner B intersects approximately one-third to one-half 40 of the side F-C of the folded triangle F-C-G; the folded portion of the rectangle thus cooperating with the folded triangle to form a sleeve 20 through which a portion of the arm and hand of the infant or child may extend.

It is to be noted that the triangular portion provides the arm, shoulder, chest and small of the back, covering and that the rectangular portion provides the covering for the remaining torso and lower limbs, as hereinafter described, although the same said triangular and rectangular portions are united in an integral garment.

The opposite edge A-X of the garment is then brought over the previously folded part of the rectangle and the corner of the rectangle intersects a point 13 approximately one-third to one-half the distance of the side G-C of the triangle F-C-G. As fastening means are carried by the side A-C of the intersecting por-

tion of the triangle A—B—C at spaced points thereof, as at 14 and 15, one such means being positioned at point A and one midway between A and F. These are used to fasten the two overlapped folded sides of spaced points 12 and 13 thereof, as above described, to the triangular chest covering.

The outer front portion of the garment A—X carrying a fastener 16 is then tapered or flared slightly with the mother's hand from the point of fastening 16a to the hem of the garment which has been created by the folding of the garment, as described herein, and is fastened midway of the length of the garment, as shown, wherefore the hem portion of the garment is operatively greater in circumference than the more folded body enveloping portion adjacent the arms.

Hence, the child has sufficient freedom to move his legs about and at the same time, the overlap of the garment provided is sufficient to keep him covered. Increased effective circumference of the lower edge provides ample room for walking, creeping or other activities. Furthermore, the undergarment or diaper may be changed without removing the child from the garment when sleeping and without the child becoming exposed.

Mothers having charge of babies or small children are familiar with the anxiety and apprehension lest the child become uncovered, catch cold, etc., during sleep, and fear of strangling, etc.

The garment is preferably made of suitable length so that the feet are well covered at all times. The garment may obviously be made in a plurality of sizes to accommodate different age children.

The advantages of this garment are readily apparent and it should be understood that the garment is not restricted to use on small children or babies as it might be used to good effect for adults in hospitals, for tubercular patients, or as sleeping bags by soldiers, campers, etc.

I am further aware that numerous and extensive departures may be made herefrom without, however, departing from the spirit of my invention or the scope of the appended claims.

I claim:

1. A one-piece garment adapted to be wrapped about an infant or small child, said garment comprising a isosceles triangular portion and a main body portion, said portions being integrally formed, the triangular portion having a neck opening disposed therein, the said triangular portion adapted to be folded upon itself to form a covering for the upper back, shoulders, arms and chest of the said infant or child, the said fold being made along a line parallel with the base of said triangle and at slightly more than one-half the altitude thereof, each of the folded and unfolded side portions of the triangle forming the unitary shoulder and arm coverings and the apex and remaining center portions of the triangle forming the chest and upper back covering, the head of the child being projected through the neck opening, a pair of spaced fasteners on one of the unfolded sides of the triangle, a main body portion integrally formed with said triangular portion and being generally of rectangular form, the sides of said body portion meeting the equi-sides of the triangle and the upper base thereof forming the lower base of the triangle, a second fastener disposed intermediate the one side edge of the body portion contiguous to the side

of the triangle carrying the pair of fasteners, the side of the garment comprising the side edges of the triangle and rectangle carrying the fasteners adapted to be overlapped over the opposite side of said garment and said fasteners adapted to be secured to the overlapped opposite side and to said folded triangular portion forming the chest covering.

2. A one-piece garment adapted to be wrapped about an infant or small child, said garment comprising an isosceles triangular portion and a main body portion, said portions being integrally formed, the triangular portion having a neck opening disposed therein, the said triangular portion adapted to be folded upon itself to form a covering for the upper back, shoulders, arms and chest of the said infant or child, the said fold being made along a line parallel with the base of said triangle and at slightly more than one-half the altitude thereof, each of the folded and unfolded side portions of the triangle forming the unitary shoulder and arm coverings and the apex and remaining center portions of the triangle forming the chest and upper back covering, the head of the child being projected through the back opening, a main body portion integrally formed with said triangular portion and being generally of rectangular form, the sides of said body portion meeting the equi-sides of the triangle and the upper base thereof forming the lower base of the triangle, one side of the garment adapted to be overlapped over the opposite side of said garment, and fasteners adapted to be secured to the overlapped opposite side and to said folded triangular portion forming the chest covering.

3. A one-piece garment adapted to be wrapped about an infant or small child, said garment comprising a generally isosceles triangular portion and a main body portion, the triangular portion having a neck opening disposed therein, the said triangular portion adapted to be folded upon itself to form a covering for the upper back, shoulders, arms and chest of the said infant or child, the said fold being made along a line parallel with the base of said triangle and at slightly more than one-half the altitude thereof, each of the folded and unfolded side portions of the triangle forming the unitary shoulder and arm coverings and the apex and remaining center portions of the triangular portion forming the chest and upper back covering, said main body portion being of substantially rectangular form, the sides of said body portion meeting the equi-sides of the triangle, and the upper base thereof forming the lower base of the triangle, one side of the garment adapted to be overlapped over the opposite side of said garment, and fastener means adapted to be secured to the overlapped portions and to said folded triangular chest covering portion.
